UNITED STATES PATENT OFFICE.

PAUL H. GRIMM, OF GLEN COVE, AND FRANK L. COCKS, OF NEW YORK, N. Y., ASSIGNEES
TO ARBUCKLE BROTHERS, OF NEW YORK, N. Y., A FIRM COMPRISING WILLIAM A.
JAMISON, CATHERINE A. JAMISON, AND CHRISTINA ARBUCKLE.

PACKAGE-FORMING MACHINE.

1,133,857.

Specification of Letters Patent. Patented Mar. 30, 1915.

Application filed March 23, 1914. Serial No. 826,637.

To all whom it may concern:

Be it known that we, PAUL H. GRIMM and FRANK L. COCKS, both citizens of the United States, residing, respectively, in 5 Glen Cove, in the county of Nassau and State of New York, and borough of Brooklyn, county of Kings, city and State of New York, have invented certain new and useful Improvements in Package-Forming 10 Machines, of which the following is a specification.

This invention relates to package-forming machines and has for an object to provide mechanism for incorporating in a container or package when the same is in process 15 of manufacture, a sheet for adding to the security afforded by the container. This is preferably a lining impervious to moisture, and may be of some suitably prepared 20 paper, thus tending to preserve from deterioration the material which is afterward placed in the package.

The illustrated embodiment of the invention is in one aspect in the nature of an 25 improvement on the Smyser machines an illustration of an example of which is to be seen in U. S. Patent No. 505,857, issued October 3, 1893.

Although the parts for feeding the additional or interlining sheets are adapted to 30 be supplied to existing machines, and when present may be used or not as occasion may demand, and may be removed entirely from the parts making up the simpler mechanism 35 without disassembling the latter, yet the new parts and the old form a unitary organization coöperative in effecting new results, and producing a new product in which the new elements enable the old elements 40 to perform new functions, the presence of the new elements enabling the old elements to produce a new product.

In the drawings accompanying this specification a practicable embodiment of the invention is illustrated in which,

Figure 1 is a side elevation of a portion of a package forming machine, certain of the parts being broken away to illustrate the relation of the parts lying beyond; Fig. 2 50 is a plan view of a portion of the device illustrated in Fig. 1, and is taken on a plane at about the line 2—2 in such figure. Fig. 2^a is an enlarged section taken on a plane at about the line 2^a—2^a of Fig. 2; Fig. 3 is a detail view partly in vertical section of the mechanism illustrated in Fig. 1, showing the parts in a different position; Fig. 4 is a somewhat similar view showing the parts in a still different position; Fig. 5 is a plan view of the mechanism shown at 55 the left hand side of Fig. 1, the driving mechanism being broken away; Fig. 6 is a section taken on a plane at about the line 6—6 of Fig. 1 looking in the direction of the arrows; Fig. 7 is an enlarged section 60 taken on a plane at about the line 7—7 of Fig. 1 looking in the direction of the arrows; and Fig. 8 is a detail plan view of the cam shaft and cams.

That portion of a package forming machine or packaging machine which supplies the paper wrappers to the folding or forming devices, is illustrated herein.

There is shown at A a stack of wrappers in position to be lifted and transferred to 75 the folding device. This stack is shown upon a suitable stack support or holder A' which is advanced automatically in some suitable manner, in the present instance a screw A² being provided for this purpose; 80 such feeding however being no part of the present improvement it is not described in detail.

The object of the mechanism illustrated is to feed forward at regular intervals sheets 85 a from the stack A and to apply to or impose upon the uppermost sheet of the stack an interlining sheet b. The sheet b is fed forward over the topmost sheet a of the stack into such a position that the lifting 90 and forwarding device will engage both sheets simultaneously and lift them and transfer them. In the Smyser machine above referred to the uppermost sheet of the stack is engaged by pasting mechanism, 95 the paste being utilized in the transferring, and after the sheet has been transferred to the folding device such paste is utilized for the purpose of holding the wrapper in its folded position. In the present mechanism 100 the added sheet is placed in such a position relatively to the position of the uppermost sheet in the stack and to the working point of the pasting and transferring mechanism,

that the imposed sheet shares the paste with the sheet of the stack. The two sheets are moved simultaneously and held together and are so fed or supplied to the folding device.

There are shown four pasting and transferring devices C which are caused to revolve step by step in steps of 90 degrees in a horizontal plane, and are also caused to reciprocate vertically, between the steps taken, from the horizontal plane. Each of these pasting devices is shown carried by an arm c, which arms are fast upon a plate c' fast upon a vertical shaft C', which shaft is mounted in suitable bearings in the framework of the machine, and is held in its upward position by yielding means. Each of the plates C is provided upon its under side with paste receiving feet c² for engaging the pasted surface of paste disk c³, which paste disk is caused to rotate and its surface thereby supplied with paste from a reservoir c⁴. The stack holder A' is disposed at a position below one of the between step positions of the plates C, and the paste disk c³ is disposed at another such position, so that these two portions of the device are disposed at angles of approximately 90 degrees about the shaft C'. In the mechanism illustrated the point of delivery of the sheets from the pasting and transferring mechanism is the matrix H disposed substantially diametrically opposite the position of the stack holder A'.
 The lining paper carried by the roll B is illustrated of less width than are the sheets a (see Fig. 2) and the lining paper is fed over the stack so that its forward edge comes to rest prior to reaching the forward edge of the uppermost sheet upon the stack, so that there is exposed a margin a' on the upper surface of the uppermost sheet of the stack at three edges of the sheet b. The pasting feet c² are of such area that they engage this exposed margin and the edge of the sheet b adjacent thereto (see dotted lines in Fig. 2). When such feet are covered with paste and are depressed upon the superposed sheets a and b, the paste which otherwise would be applied to the surface of sheet a is shared by it with the sheet b, and upon the rising of the pasting device the two sheets are raised and transferred together.

Suitable mechanism is provided for unwinding and advancing the paper from the roll B. In the present instance the sheet or stock of paper is pushed forward by rotating the roll and by means of suitable roller guides is again pushed forward over the stock and the sheet is there severed from the stock. The roll is shown mounted upon a spindle b' which has fast with it a ratchet wheel b² which is engaged by a reciprocatory pawl b⁸. The pawl is carried by a pitman b⁴ pivoted to one end b⁶ of a bell crank, the

other end b⁸ of which is operated by mechanism presently to be described.

A certain amount of adjustable overthrow is provided for the pawl b⁸. It is shown longitudinally movable in the pitman b⁴ and is held in its adjusted position by means of a suitable set-screw b⁷. By this means the amount of movement imparted to the roll by uniform oscillations of the bell-crank b⁸ b⁹ may be adjustably varied as desired. An antifriction roll b⁸ is provided for holding the pawl b⁸ to its work. One great difficulty experienced in this class of mechanism is overcoming the inertia of the roll of paper B, and guarding against the momentum which it acquires when advancing the stock of paper step by step. Considerable leverage is afforded by the present mechanism, and the paper is started forward and advanced without undue strain to the parts of the machine or to the paper itself, and the paper is accurately measured, and positively stopped at the predetermined position.

The stock of paper from the roll B is led to idler rolls b⁹, and to a pair of guiding and forwarding rolls b¹⁰ b¹¹ which, in the present illustration are positively driven. In the present illustration the lower roll is made of smooth brass and the upper roll is made of smooth rubber. A support b¹² is provided for the paper in case the amount fed from the roll is in excess of the demand of the rolls b¹⁰ b¹¹. A guide b¹³ is provided in front of the rolls b¹⁰ b¹¹ for similar reasons. At the discharge side of such rolls a funnel-shaped guide b¹⁴ is provided. Suitable shears are provided for severing the stock adjacent the stack A. Such shears in the present illustration comprise a fixed blade b¹⁵ and a movable blade b¹⁶. A supporting plate b¹⁷ is provided at the stack side of the shears for supporting the rear edge of the sheet b after this has been severed from the stock. A coiled spring b¹⁸ is provided for normally holding the shear blades open. Irregularities frequently occur in the rolls of lining stock B, sometimes in the cores on which the rolls are wound, sometimes in the paper itself being thicker at one side than at the other; to assure the accurate feed, one of the rolls b⁹ in the drawings the upper of these rolls, is mounted in a shiftable box b⁹⁰, engaged by adjusting screws b⁹¹ b⁹² whereby such irregularities or inequalities may be rectified by adjusting the position of such roll.

The main driving shaft of the machine is shown at D, and is driven by a pulley d. This shaft is shown having fixed upon it a worm d' meshing with a worm-wheel d² which is fast with a shaft d³ carrying a bevel gear d⁴ meshing with a bevel gear d⁵ which is fast on the cam shaft d⁶. Upon the cam shaft d⁶ are mounted the driving cams of the machine. The cam wheel d⁷ is pro-

- vided with a groove for receiving the antifriction roller in the end of a lever d^8 , which lever is connected by means of a link d^9 with an arm c^5 carried by a hub c^{50} loose on the shaft C' . The plate c' is shown provided with four holes c^{10} for receiving a lug c^{11} on the under side of the arm c^5 when the shaft C' is in its elevated position. The throw of the lever d^8 is so adjusted and the connections so proportioned that at each rotation of the cam shaft the plates C are rotated through an angle of 90 degrees. A cam wheel d^{10} is also mounted upon the cam shaft and is provided with a groove for receiving the antifriction roller of a lever d^{11} which is connected by means of a link d^{12} with a head member d^{13} carried by the upper end of the shaft C' . The cam groove and associated parts are so proportioned and timed that after the plates C have been stepped around 90 degrees in a horizontal plane, the plates will be forced downward, bringing the paste feet c^2 of one pasting and transferring plate in engagement with the surface of the paste disk c^3 , and bringing the paste feet of the preceding plate in engagement with the superposed sheets a b at the top of the stack. The head d^{13} is provided with an opening in each corner, which openings register with guide pins d^{14} suitably carried by the machine frame and provided with conical ends for the purpose of justifying the position of the plate c' at the beginning of its descent and for guiding it in a true line. The shear blade b^{16} is provided with an upstanding end b^{18} located in the path of movement of shear actuating devices b^{20} carried by the plate c' upon the descent of the shaft C' .
- There is shown mounted on the driving shaft D a worm e meshing with a worm wheel e' mounted upon a shaft e^2 , which shaft is shown provided with a bevel gear e^3 meshing with a bevel gear e^4 fixed upon a shaft e^5 , which shaft is the driving shaft for intermittently feeding the stock forward for supplying the interlining sheets b . The continuously rotating driver E for such portion of the mechanism is shown fast upon shaft e^6 . This driver in connection with suitable engaging mechanism is timed for stepping the gear wheel e^6 forward at suitable times to feed the interlining sheets over the uppermost sheet of the stack at such times as the pasting and transferring mechanism is out of the path of movement of the oncoming interlining sheet. This mechanism comprises an intermittent clutch. The gear wheel e^6 is mounted free upon a flange e^7 (Fig. 7) which forms a part of the bearing for the shaft e^6 and the driver E . This flange is carried by a plate e^8 securely fastened to the framework of the machine. The driver E is of disk formation cut away and having a finger e^9 for engaging, when in proper position, the pins e^{10} carried by the wheel e^6 . In the present illustration there are four of these pins set at angles of 90 degrees one to the other about the axis of rotation of the wheel e^6 . These pins are shown mounted in pockets e^{11} and are pressed away from the path of movement of the finger e^9 by suitable springs carried by such pockets. A cam track e^{12} is shown fastened to the plate e^8 . Such track is a segment of a circle slightly longer than 90 degrees, and is provided at its forward end with a bevel face upon which the pins e^{10} ride up. Rotation of the wheel e^6 will cause one of the pins to ride up this inclined face and on to the flat portion of the track, which will then bring the outer end of the pin into position to be engaged by the finger e^9 . The finger will then move the wheel e^6 forward until the pin which it is engaging runs off the end of the track and is returned to idle position by means of its spring. This will then release the wheel e^6 from the engagement of the actuator E and permit such actuator to move forward idly. Just prior to the pin which is in engagement with the finger running off the track, the pin behind it runs up on the inclined surface and on to the level surface of the track and is in position to engage the finger e^9 upon its next rotation, that is, the finger e^9 is in engagement with a pin through 90 degrees of its rotation and moves from engagement with a pin and idle during 270 degrees of its rotation. One portion of the plate forming the actuator E constitutes a cam e^{13} upon its edge. This portion of the plate is provided with a raised rib e^{14} for clearing the pins e^{10} and their pockets. The serrated face of the cam e^{13} actuates the pawl b^3 through the roll f^5 , bell crank b^5 b^6 and pitman b^4 . A brake F is provided for the roll B , or its carrier, and engages a friction face f fast with the shaft which carries the roll material. This brake is actuated by means of the cam face e^{13} . The depressions forming the serrations for actuating the pawl b^3 are not sufficiently deep to permit the brakes to become active. The brake is carried by a stem f^2 and is pressed toward its work by means of a coiled spring f^3 . It is raised by means of the lever f^4 which carries a roll f^5 running upon the cam face e^{13} . The lever f^4 is pivoted at f^{40} , and is connected to the brake stem f^2 by means of a link f^{20} . Adjusting means is provided for the brake in the form of a nut f^6 mounted upon the stem f^2 . It has been found desirable to assist the forwarding rolls in advancing the stock from which the lining sheets b are severed. To this end the roll B is unwound or rather it is rotated in such a direction that the material unwinds from it to approximately meet the demand of the forwarding rolls

b¹⁰ b¹¹ which measure the paper and push the sheet forward through the shears and over the stock. The actuation of the roll and roll-holding mechanism is accomplished by the pawl and ratchet mechanism above described. The forwarding rolls are supported in the present instance by means of a bracket *b²¹* secured to the main frame. The rolls are provided respectively with intermeshing pinions *b²² b²³*. The rolls are protected by means of housings *b²⁴ b²⁵*; *b²⁴* is shown secured directly to the bracket *b²¹* and the housing *b²⁵* is shown secured to a plate *b²⁶* which is adjustably secured by means of set-screws to the bracket. Set-screws *b²⁷ b²⁸* are provided for engaging the plate *b²⁶* and the end of the housing *b²⁵* for forcing the rolls together.

As stated above the roll *b¹⁰* is provided on its outside with a rubber face and the roll *b¹¹* is provided with a brass face. In the present gearing at each period of movement of the sprocket wheel *G* the forwarding rolls will advance 5 revolutions and accurately measure the lining sheet *b*. The rolls *b¹⁰ b¹¹* are shown driven in the following manner: One of the rolls, as for instance the lower roll *b¹¹*, has fast with it a sprocket wheel *g* (Fig. 6) over which runs a sprocket chain *g¹* running over the driving sprocket *G*, which sprocket has fast with it a pinion *g²* meshing with an idler *g³* (Fig. 1) which meshes with the spur gear *e⁶* which is intermittently driven by the continuously advancing actuator *E*. *g² g³* are mounted on shafts *g⁴ g⁵*, and are each provided with a hub for the purpose of brake engagement. The brake *g⁶* is wedge-shaped and provided with a plunger *g⁷*. The brake is held to its work by means of a coiled spring *g⁸*. The plunger *g⁷* is articulated to the lever *f⁴* which actuates the brake *F* and is actuated concurrently therewith. A drag brake *g⁹* is shown (Figs. 3 and 4) continuously in engagement with the hub associated with the sprocket wheel *G*. A hand lever *f⁷* (Fig. 6) is provided for raising the brakes when it is desired to rapidly feed forward the paper from the roll by hand in setting up the machine or when it is desired to remove one roll and replace it by another. A catch *f⁸* is shown for engaging the hand lever and holding the brakes in their inoperative position.

Each of the pasting and transferring devices stops in turn over the matrix *H*, the matrix and associated parts here illustrated being substantially those illustrated in the Smyser patent above referred to. Upon the downward movement of the transferring devices the interposed sheets *a b* are placed upon the upper surface of the matrix, whereupon the stripper *I* descends and holds the sheet or sheets in position during the upward movement of the transferring de-

vice. The stripper is illustrated in dotted lines in Fig. 5. After the stripper and the transferring device have been sufficiently advanced in their upward movement, the matrix *H* is advanced toward the formers 70 *J J*.

The operation of the machine is substantially as follows:—The pasting and transferring devices illustrated operate substantially in the manner set forth in the Smyser patent above referred to and their operation will not, in this part of the description, be specifically mentioned except in connection with the explanation of the associated parts, except to state that at time intervals the paste-covered feet *c²* come into position over the stack *A* and descend and rise and advance. At each descent the paste-covered feet will engage the uppermost sheet of the stack, apply paste thereto and utilize such paste 80 in raising and forwarding the uppermost sheet of the stack. After a sheet *a* has been raised the present mechanism will supply beneath it one of the extra lining sheets as a rider for the uppermost sheet of the stack 90 by forwarding the lining sheet to position. The mechanism for forwarding and severing the rider or lining sheet is timed in such relation to the actuation of the pasting and forwarding mechanism that such rider sheet 95 will be in position for sharing with the uppermost sheet of the stack the engagement of the lifting and forwarding mechanism. The shaft *e⁵* for the actuator *E* of the sheet-supplying mechanism is shown driven by the 100 same shaft which drives the cam shaft *d⁶* for controlling the horizontal step-by-step movement of the pasting and transferring mechanism as well as its vertical movement for engaging the sheet and lifting the same. 105 In the position illustrated in Fig. 1 the paste-covered feet *c²* are at the end of their upward stroke, having descended upon a sheet *a* at the top of the stack, having imposed upon it a sheet *b*, leaving a margin *a¹* 110 for the reception of the paste and lifted the same. As is stated above, the feet *c²* are of sufficient area to apply paste to this exposed portion *a¹* and to the adjacent edges of the imposed sheet *b*. The next movement of the 115 pasting and transferring mechanism is in a substantially horizontal plane, and during which movement the finger *e⁶* of the actuator *E* is timed to come into engagement with the pin *e¹⁰* which was advanced in its path just prior to its disengagement from the pin with which it was previously in engagement. This engagement between the pin *e¹⁰* and the finger *e⁶* causes the spur gear *e⁶* to move forward 90 degrees, which forward movement, 120 upon its inauguration depresses the roll *f⁶* and removes the brakes from engagement with the hubs of the pinions *g² g³* and from the friction face of the holder for the roll of paper stock *B*. The forward movement 125

of the parts is then permitted. The driver G then starts the rotation of the forwarding rolls b¹⁰ b¹¹, at the same time the serrated cam edge e¹³ oscillates the bell crank b⁸ b⁶ and reciprocates the pawl b⁹, thereby advancing the roll carrier step by step and causing the material to unwind therefrom and be fed forward to the forwarding rolls which then push the paper forward over the stack A. After a predetermined amount of paper has been fed forward the cam e¹³ runs off the roller f⁶ whereupon the lever f⁴, and the brakes respond to their respective springs and the actuating mechanism and the paper-forwarding mechanism come to a standstill. The rollers b¹⁰ b¹¹ positively position and hold the sheet until it is severed. At the time the cam runs off the roll f⁶ the pin e¹⁰, which has been engaged by the finger e⁹ for imparting the forward movement to the spur wheel e⁶, runs off its track e¹² and is drawn out of engagement with the finger by means of its spring. At about the time the forwarding rolls b¹⁰ b¹¹ have been brought to rest the pasting and transferring device is in position over the stack and is then caused to descend. In its descent the shear-actuating foot b²⁰ engages the end of the shear b¹⁹ and severs the sheet which has been placed in position at the top of the stack, and the continued descent of the pasting device brings the feet c² into engagement with the superposed sheets in the manner above described. It is to be noted that the cam for effecting the unwinding of the paper from the roll B also controls the brakes for the roll and for the forwarding mechanism for the material unwound.

It will be apparent that changes may be made in the mechanism within the scope of the claims without departing from the spirit of the invention.

What we claim is:—

1. The combination with sheet supporting means, of sheet shifting means embodying mechanism adapted for engaging the upper face of a sheet upon such support, raising the same therefrom and transferring the same and functioning in timed sequence, and a sheet supplying device adapted for laying a rider sheet upon such sheet prior to the engagement of the shifting device therewith.

2. The combination with sheet supporting means, of sheet shifting means embodying mechanism adapted for engaging the upper face of a sheet upon such support, raising the same therefrom and transferring the same and functioning in timed sequence, and mechanism for imposing a sheet upon the said sheet in position to share with the same the engaging contact of the shifting means.

3. The combination with sheet-supporting means of mechanism for pasting and transferring the sheet from such supporting

means, and mechanism for imposing a sheet upon the said sheet in position to share with the same the paste from the pasting mechanism.

4. The combination with sheet-supporting means of mechanism for pasting and transferring the sheet from such supporting means, and mechanism for imposing a sheet upon the said sheet in position to share with the same the paste from the pasting mechanism, and driving mechanism for actuating said pasting and transferring mechanism and imposing mechanism in timed sequence.

5. The combination with a sheet-shifting device comprising a combined paster and transferer adapted for pasting and transferring in timed sequence, of a sheet-supplying device adapted for laying a rider sheet upon each such sheet prior to the application of paste thereto.

6. The combination with mechanism for pasting and transferring sheets of paper from a stack of sheets to package-forming devices, of mechanism for imposing a second sheet upon such stack sheet in succession, in such position relatively thereto and to the working position of the pasting device, that said second sheet shares the paste with the stack sheet.

7. The combination with mechanism for pasting and transferring by the aid of the paste supplied by such paster, sheets of paper from a stack of sheets to package-forming devices, of mechanism for imposing a second sheet upon such stack sheet in succession in such position relatively thereto and to the working position of the pasting device that said second sheet shares the paste from the paster with the stack sheet.

8. The combination with a holder for a stack of sheets, shears adjacent thereto, a feeder for feeding a strip of material through the shears and onto the stack on said holder, a sheet conveyer, means for depressing the conveyer upon the stack, a shear actuator carried by the conveyer and adapted to actuate the shears upon the approach of the conveyer to the stack, and means for driving the conveyer and feeder in synchronism.

9. In a device of the character specified, the combination with a stack holder, of pasting and transferring mechanism for engaging the sheets upon the stack, a holder for a roll of paper, means for unwinding the roll step by step, means for forwarding the paper so unwound over the stack, a shear located adjacent the stack, and means timed with the pasting and transferring mechanism for actuating the shear.

10. Mechanism for intermittently supplying sheets and comprising a roll holder, pawl and ratchet mechanism for actuating the same for unwinding material therefrom, forwarding rolls for the unwound ma-

- terial, gearing for driving said forwarding rolls embodying a gear wheel, a series of pins carried by the gear wheel, a track for engaging said pins and elevating the same, a continuously rotating driver provided with a finger for engaging an advanced pin, and a cam for actuating said pawl and ratchet mechanism.
11. Mechanism for intermittently supplying sheets and comprising a roll holder, pawl and ratchet mechanism for actuating the same for unwinding material therefrom, forwarding rolls for the unwound material, gearing for driving said forwarding rolls, embodying a gear wheel, a series of pins carried by the gear wheel, a track for engaging said pins and elevating the same, a continuously rotating driver provided with a finger for engaging an advanced pin, a cam for actuating said pawl and ratchet mechanism, and a brake for the roll holder controlled by said cam.
12. Mechanism for intermittently supplying sheets and comprising a roll holder, pawl and ratchet mechanism for actuating the same for unwinding material therefrom, forwarding rolls for the unwound material, gearing for driving said forwarding rolls embodying a gear wheel, a series of pins carried by the gear wheel, a track for engaging said pins and elevating the same, a continuously rotating driver provided with a finger for engaging an advanced pin, and a cam for actuating said pawl and ratchet mechanism, and a brake for said roll holder and for such gearing controlled by said cam.
13. In a device of the character specified, the combination with a roll holder, of mechanism for rotating the holder for unwinding the material of the roll thereon, of mechanism for forwarding the material so unwound, driving mechanism for intermittently actuating the unwinding and for warding mechanism, brakes for the roll holder and forwarding mechanism, and actuating means for positively applying the brakes.
14. In package-forming mechanism, the combination with a wrapper sheet support, of mechanism for imposing a lining sheet on a wrapper sheet on such support in position to expose portions of the upper side of such wrapper sheet, a paster constructed and adapted for applying paste to parts of such exposed portions of the wrapper sheet and to the lining adjacent thereto and for raising and forwarding the sheets in such imposed position.
15. In a device of the character specified, the combination with roll supporting means, of roll unwinding means for advancing stock from the roll, a brake for the roll, forwarding means for the advanced stock, a brake for the forwarding means, and a continuously rotating actuator for periodically releasing the said brakes and actuating the unwinding and forwarding means.
16. In a device of the character specified, the combination with roll supporting means, of roll unwinding means for advancing stock from the roll, a brake for the roll, forwarding means for the advanced stock, a brake for the forwarding means, a continuously rotating actuator for periodically releasing the said brakes and actuating the unwinding and forwarding means, and a drag brake continuously operative upon the roll unwinding means.
